UNITED STATES PATENT OFFICE.

RICHARD HUBERT PYBUS, OF DERBY, ENGLAND.

SELF-FITTING CANDLE.

Application filed January 20, 1925. Serial No. 3,635.

To all whom it may concern:

Be it known that I, RICHARD HUBERT PYBUS, a subject of the King of Great Britain, residing at Derby, in the county of Derby, England, have invented certain new and useful Improvements in Self-Fitting Candles, of which the following is a specification, reference being had therein to the accompanying drawing.

10 This invention relates to candles of circular section made from paraffin, stearine, ceresine and the like. A defect with such candles is that they rarely fit the hole in the average candle-stick, being generally a loose fit, necessitating packing with paper and the like.

I propose to make such candles self-fitting within ordinary limits, by forming integrally with the candle material, a rib 20 or ribs, (hereinafter called ribs) at the base of the candle of sufficient height from the base to conform with the average depth of the hole in the average candlestick.

In the accompanying drawing, Fig. 1 is 25 a side view of a candle embodying one form of my invention.

Fig. 2 is an end view of the same.

Fig. 3 is a side view of a modification.

It is generally known that self-fitting 30 candles of circular section have been made with ribs at the base, but it was always considered necessary to have these ribs taper, concentrically with the candle, the ribs having the bigger external diameter at the 35 point furthest removed from the base. This construction called for special moulding machinery as the taper part had to be moulded in moulds withdrawing one way, whilst the candle proper was being moulded 40 in moulds withdrawing in the opposite direction. Such machines were slow in operation and the resulting self-fitting candles were always considerably more expensive than the plain ones.

45 I am aware also that fancy candles of circular cross-section have been manufactured with longitudinal ribs or recesses or with a scroll twist or spirals extending the full length of the candle also with a worm 50 or thread in the form of a screw on the lower end of the candle so that it may be retained firmly in the ordinary candlestick.

55 My proposal is to make the external surface of the ribs parallel with the external surface of the candle itself (which tapers from butt to tip) so that the candle and the

ribs can be moulded in the same mould, withdrawing in the same direction. I do not restrict myself to any particular section of rib or to any particular number of ribs 60 which may range from one upwards or to the distance that the ribs extend from the base or butt of the candle, subject that such distance does not exceed 1''. Further the centre line of the ribs may be either parallel 65 with the axis of the candle or form a spiral round the axis of the same, subject that the spiral is not so acute as to assume the shape of a screw or to prevent the candle from being ejected from the mould merely 70 by thrust applied at the top end. The latter does not necessarily show any improvement over the former, but it is a possible form, as spirals can be withdrawn from the mould, the candle moving with a spiral 75 motion in conformity.

The essence of my proposals is to make candles of circular section self-fitting to the candlestick by the formation of ribs on the surface at the base of such candles as easily 80 as common candles of plain circular section can be made.

Such candles as I propose making will be self-fitting by virtue of the soft-external 85 edges of the ribs forming themselves to the hole in the candlestick, a tight fit resulting.

While I do not restrict myself in regard to the number of ribs on each candle there is obviously some number that is most suitable. The number that seems to give the best 90 results is three equi-distant ribs which is the smallest number that gives secure location.

Further I do not restrict myself as regards the section or relative size of the ribs, 95 but to make same of a semi-circular section with the flat part towards the candle gives good results. A triangular, square or other section would suit, but would not have any advantage over the one first mentioned. The 100 radii of the semi-circular ribs may be one quarter of the radius of the candle section and it is obvious that it is best to keep the rib relatively thin as compared with the candle itself.

105 The form of candle embodying my invention and shown in Figures 1 and 2 of the drawing is the one I prefer to adopt as it is found that this form can be manufactured readily and cheaply and in use ful- 110 fils the object aimed at in a successful manner.

In such form it will be observed that the body 2 of the candle has formed upon it at the butt end three ribs 1 equidistantly disposed about said body and of semi-circular cross section. The important feature about these ribs is that they are not tapered or bevelled at or towards the lower end as has heretofore been the case but, on the contrary, they are made parallel to the side 10 of the body 2 which is slightly tapering from base to tip. They therefore have their greatest diameter at the base, which is exactly opposite to ribbed candles as previously made. In fact the candle has its 15 largest diameter at the base or butt and at this region is not bevelled or tapered. The three ribs constitute what is found in practice to be an excellent means for rendering the candle self-fitting for not only is a three- 20 point contact obtained in the candlestick but the small number of ribs do not offer much resistance to the forcing of the butt end into the hole. A larger number of ribs offer more resistance than is desirable 25 as it naturally follows that with a larger number of ribs a greater amount of material requires to be stripped from the butt end i. e. from the external faces or sides of the ribs as the candle is inserted by force 30 into the hole in the candlestick.

Alternatively the ribs 1 may be inclined on the body 2 as shown in Figure 3 but in any case it is to be noted that the butt end of the candle is non-tapered which feature 35 enables the article to be moulded and withdrawn in a simple manner.

With regard to the height from the butt that the ribs extend up the sides it is obvious that it serves no useful purpose to

carry same higher up than is the depth of 40 the hole in the average candlestick. I find for a candle 6 inches from butt to tip a height of $\frac{3}{4}$ inch sufficient.

The external surfaces of the ribs ought, theoretically, to taper towards each other 45 from the butt end of the candle to the tip end and this they will do if same are made parallel to the face of candle as the candle has on it a slight taper from butt to tip. The small relative height I propose making 50 the ribs, however, obviates any disadvantage in moulding if the external surfaces are parallel to the axis of the candle as the shrinkage of the candle material in moulding enables the latter construction to still 55 leave the mould. To make these external surfaces parallel gives good results.

It is not essential that the centre lines of the ribs are parallel with the axis of the candle but this construction gives the better 60 result. The other alternative of making the ribs form spirals round the candle is a complication that in reality gives no better result.

What I claim then is:—

A candle of circular cross section having formed integrally therewith, at its butt end, a plurality of ribs equally distant apart and longitudinally of the candle, the distance 70 between the ribs being greater than the width of the ribs and providing spaces for the reception of material displaced circumferentially from the ribs in fitting a candle to a socket.

In testimony whereof I affix my signature.

RICHARD HUBERT PYBUS.
